UNITED STATES PATENT OFFICE.

SAMUEL J. SHIMER, OF MILTON, PENNSYLVANIA.

CUTTER-HEAD.

SPECIFICATION forming part of Letters Patent No. 668,586, dated February 19, 1901.

Application filed December 5, 1900. Serial No. 38,771. (No model.)

To all whom it may concern:

Be it known that I, SAMUEL J. SHIMER, a citizen of the United States, residing at Milton, in the county of Northumberland and State 5 of Pennsylvania, have invented new and useful Improvements in Cutter-Heads, of which the following is a specification.

My invention relates to expandable cutter-heads of the Shimer type; and the objects of 10 the same are to provide simple and efficient means for adjusting the two head-sections of a cutter-head relative to each other to regulate the width of the groove cut by the bits and to provide a locking device to prevent 15 the adjustment being disturbed.

With these objects in view I have designed the novel construction fully described in this specification and claimed and illustrated in the accompanying drawings, forming a part 20 thereof, in which—

Figure 1 is an elevation of my improved cutter-head. Fig. 2 is a vertical longitudinal section of the same. Fig. 3 is a detail perspective of the spring locking-ring. Fig. 4 25 is a perspective of a fragment of the adjusting-nut. Fig. 5 is a perspective of the locking-nut.

Like characters of reference designate like parts in the different views of the drawings. 30 The letter A designates the lower head-section, which section is provided with a hollow hub 2. This hub 2 has a lower smooth cylindrical portion 3 and a smaller upper portion 4. A square shoulder 5 is formed at the 35 junction of the portions 3 and 4. For a short distance above the shoulders 5 at 6 the stem 4 is smooth. Next comes a threaded portion 7 and then an upper smooth portion 8. The second or upper head-section is designated 40 by the letter B, and this section has a hub 9 formed integral therewith. The interior bore 10 of the hub 9 fits snugly the smooth portion 3 on the hub 2. The hub 9 when the sections A and B abut extends up to a point 45 about one-fourth of an inch below the shoulders 5. This intervening distance 10^a is the range of adjustment of the cutter-head and may be varied to suit different sizes of work. Two shoulders or ledges 11 and 12 are formed 50 on the outer contour of the hub 9, and the distance 13^a between them is made equal to the distance 10^a. Projecting above the ledge

12 is a threaded portion 13, which fits an adjusting or carrier nut 14. This adjusting or carrier nut 14 is turned out at 15, leaving a 55 rim 16 and a ledge or shoulder 17, designed to fit snugly the ledges 11 and 12, respectively, when the cutter-head is expanded to its fullest extent. Just above the shoulder 17 is a threaded portion 18, which fits the before-mentioned threaded portion 13 on the section B. This arrangement, in combination with an inwardly-extending flange 19, which fits closely the portion 6 and rests on the shoulders 5, enables the sections A and B to be adjusted relative to each other by means of the nut 14. Projecting above the flange 19 is a rim 20, which thus provides a seat for a spring-ring 21 for locking the adjusting-nut in place. This ring 21 is cut by a radial slot 22 and 70 tapers on its under side from a point diametrically opposite the slot 22 toward one end. A wedge-shaped pawl 23 is located at the smaller end and extends perpendicular to the upper face of the ring. Although the ring 75 21 is tapering, its upper face is located in a plane perpendicular to the axis of rotation, which necessitates an intervening space 22^a between the flange 19 and the spring. A set-screw 23^a firmly clamps the ring 21 in place. A 80 locking-nut 24, which is interiorly screw-threaded, fits the threaded section 7. This nut 24 has an annular projection 25 formed on its under face, which projection is cut by a series of radial V-shaped grooves 26 and bears 85 against the ring 21. By this combination of adjusting-nut 14, pawl-bearing spring-ring 21, and a radially-grooved locking-nut 24 the nut 14 is held against accidental displacement by the action of the pawl in engaging 90 the grooves 26, but is at the same time left free to be turned by a slight application of force. Since both the pawl and grooves bevel in both directions, the grooves ride over the pawl in both directions. A conical-pointed 95 set-screw 27 fits a threaded aperture 28 in the locking-nut and extends into a recess 29 in the hub 2, and thereby secures the nut in place.

In assembling my device the two sections A and B are first put together and the adjusting-nut 14 slipped on, after which the locking-nut 24 is screwed on and secured by the screw 27. The head is now expanded by turning the nut 14 until the desired width is secured.

The hubs may be graduated, so that the expansion can be read off directly, or a scale may be supplied which corresponds with the radial grooves in the lock-nut and the amount 5 of expansion determined by counting the clicks of the pawl and then reading the corresponding distance off the scale.

The principal advantages gained by the construction described is that all longitudinal movement—that is, movement of translation of the adjusting-nut 14, more accurately termed a "carrier-nut"—is avoided and the relative adjustment of the two sections of the head accomplished by a simple 15 rotation of said nut. Since the nut 14 rests on the shoulder 5, it is held firmly in place by the locking-nut 24, which fits snugly the outer rim of the upper face thereof against every movement but that of rotation about 20 the hub. The spring-pawl 23 prevents accidental displacement, but permits movement of rotation by a slight application of force.

Having thus described my invention, what I claim as new, and wish to secure by Letters 25 Patent, is—

1. In a cutter-head, the combination, substantially as described, of a first head-section provided with a hub, a second head-section provided with a hub slidingly mounted on the 30 hub of said first section, an adjusting-nut mounted on the hub of said first section and fitting threads on the hub of said second section, and means for locking said adjusting-nut against accidental displacement.
2. In a cutter-head, the combination, substantially as described, of a first head-section provided with a hub, a second head-section provided with a hub slidingly mounted on said first section, an adjusting-nut mounted on 40 said first head-section and fitting threads on said second head-section, a slotted spring-ring bearing a pawl, and a locking-nut provided with grooves which are engaged by said pawl.
3. In a cutter-head, the combination, of a first head-section provided with a hub, a second head-section provided with a hub slidingly mounted on the hub of said first section, an adjusting-nut mounted on the hub of said 45

first section and fitting threads on the hub of 50 said second section, and means for holding said adjusting-nut against longitudinal movement but permitting a movement of rotation, substantially as described.

4. In a cutter-head, the combination, of a first head-section provided with a hub, a second head-section provided with a hub slidingly mounted on the hub of said first section, an adjusting-nut mounted to revolve on the hub of said first section and resting on a shoulder thereon and fitting threads on the hub of 60 said second section, and a locking-nut bearing on said adjusting-nut and thereby holding it against all movement but that of rotation, substantially as described. 65

5. In a cutter-head, the combination, of a first head-section provided with a hub, a second head-section provided with a hub slidingly mounted on the hub of said first section, an adjusting-nut mounted on the hub of said 70 first section and fitting threads on the hub of said second section, means for holding said adjusting-nut against all movement but that of rotation, means for holding said adjusting-nut against an accidental movement of rotation, substantially as described.

6. In a cutter-head, the combination, substantially as described, of a first head-section provided with a hub which has a shoulder thereon, a second head-section provided with 80 a hub slidingly mounted on the hub of said first head-section, an adjusting-nut having an inwardly-extending flange which rests on said shoulder, and threads which fit threads on the hub of said second head-section, a tapering spring-ring provided with a pawl and secured to said adjusting-nut, and a lock-nut mounted on the hub of said first section and provided with grooves constructed to be engaged by said pawl. 85

In testimony whereof I have hereunto set my hand in presence of two subscribing witnesses. 90

SAMUEL J. SHIMER.
